United States Patent Office

Des. 224,768

Patented Sept. 19, 1972

224,768

ARTICLE SUPPORT RACK

Donald Watamura, West Hempstead, N.Y., and Everett L. Duester, Holland, Mich., assignors to Herman Miller, Inc., Zeeland, Mich.

Filed Sept. 17, 1970, Ser. No. 25,041

Term of patent 14 years

Int. Cl. D6—99

U.S. Cl. D6—177

FIG. 1

FIG. 2.

FIG. 3.

FIG. 4.

FIG. 1 is a perspective view of the article support rack;
FIG. 2 is a plan view of the article support rack;
FIG. 3 is a front perspective view of the article support rack shown in FIG. 1; and

FIG. 4 is a partially rear elevation of the article support rack.

We claim:

The ornamental design for an article support rack, substantially as shown and described.
